[57] CLAIM

The ornamental design for a shoulder bib, as shown and described.

DESCRIPTION

FIG. 1 is left front perspective of a shoulder bib, showing my new design;

FIG. 2 is a top plan view, thereof;

FIG. 3 is a bottom plan view, thereof; and,

FIG. 4 is a rear elevational view, taken from the rear edge of the article as shown in FIG. 3.

The upper torso of a human shown in light line in FIG. 1 is included solely for illustrative purposes.
